CLAIM

The ornamental design for a makeup mirror support, as shown and described.

DESCRIPTION

FIG. 1 is a perspective view of a makeup mirror support showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the makeup mirror support where the makeup mirror support is in a configuration of use; and,

FIG. 10 is a perspective view of the makeup mirror support where the makeup mirror support is in another configuration of use.

The dash-dash broken lines in the drawings depict portions of the makeup mirror support that form no part of the claimed design.

1 Claim, 10 Drawing Sheets
